UNITED STATES PATENT OFFICE

104,284

DESIGN FOR A GAME BOARD

Ferdinand C. H. Müller, Swanton, Ohio

Application February 1, 1937, Serial No. 67,381

Term of patent 7 years

To all whom it may concern:

Be it known that I, Ferdinand C. H. Müller, a citizen of the United States and resident of Swanton, county of Fulton, and State of Ohio, have invented a new, original, and ornamental Design for a Game Board, of which the following is a specification, reference being had to the accompanying drawing, forming a part thereof.

In the drawing, the figure is a plan view of a game board showing my new design.

The game board is of no appreciable thickness.

I claim:

The ornamental design for a game board, substantially as shown and described.

FERDINAND C. H. MÜLLER.
